Primary Examiner — Antoine D Davis(74) *Attorney, Agent, or Firm* — Michael J. Porco; Gerald E. Hespos; Matthew T. Hespos(57) **CLAIM**

The ornamental design of a “multi-feeder power monitor”, as shown and described.

DESCRIPTION

FIG. 1 is a front perspective view of a multi-feeder power monitor of our new, original and ornamental design;

FIG. 2 is a rear perspective view of the multi-feeder power monitor of FIG. 1;

FIG. 3 is a top plan view of the multi-feeder power monitor of FIG. 1;

FIG. 4 is a rear elevational view of the multi-feeder power monitor of FIG. 1;

FIG. 5 is a right side view of the multi-feeder power monitor of FIG. 1;

FIG. 6 is a left side view of the multi-feeder power monitor of FIG. 1;

FIG. 7 is a front elevational view of the multi-feeder power monitor of FIG. 1; and,

FIG. 8 is a bottom plan view of the multi-feeder power monitor of FIG. 1.

The broken lines shown in FIGS. 1-8 form no part of the claimed design.
